UNITED STATES PATENT OFFICE.

THOMAS NEILSON, OF LONDON, ENGLAND.

HEATING, COOLING, AND VENTILATING APPARATUS.

1,399,147.

Specification of Letters Patent. Patented Dec. 6, 1921.

Application filed January 17, 1920. Serial No. 352,223.

To all whom it may concern:

Be it known that I, THOMAS NEILSON, a subject of the King of Great Britain, residing at London, England, have invented certain new and useful Improvements in and Connected with Heating, Cooling, and Ventilating Apparatus, of which the following is a specification.

This invention has reference to heating, cooling and ventilating apparatus and parts connected therewith, and has particular reference to apparatus of the type suitable for use on board ship, and adapted to be set in position as a single unit, all the parts being contained in an inclosing casing. In the known type of apparatus a fan or blower is employed to pass air through the casing, and valves are fitted for varying the course of the air current either causing it to pass through a temperature varying means or clear thereof.

The object of the present invention is to provide improvements in apparatus of the above character whereby they are of very compact form and of improved efficiency, the combination of these two features in the one apparatus being obtained by an improved construction and arrangement of parts.

According to this invention the valves controlling the ingress and egress of the air are interdependent in their operation being controlled and operated by a single lever, and are contained in adjoining compartments being separated one from the other by a division member which subdivides part of the casing and at the same time enables each subdivision to be placed in communication with a part of the casing leading to the atmosphere, the position of the valves determining which subdivision is in communication with such part of the casing.

This arrangement of subdivided chambers with interdependently operating valves enables a reversal of direction of air currents to be obtained without reversing the direction of rotation of the fan or blower.

Heretofore it has been proposed to change the direction of flow through such apparatus without changing the direction of rotation of the fan or blower by the use of interdependent valves, one of which closes the conduit for fresh air to the eye of the fan, and the other breaking the conduit from the fan

to the heating apparatus by being formed as a removable cover thereto.

The foul air was then conducted from the distributing pipe to the eye of the fan, and passing through the fan, and avoiding the heater by closing the conduit to the heater, and completing the passage of the foul air from the fan discharge, was permitted to flow into the atmosphere by means of a curved plate, pivotally mounted on a spindle, and operated conjointly with the valve closing the conduit of the fresh air to the eye of the fan. This valve at the same time completed the passage for the foul air thereto, and was formed as a curved plate pivotally mounted on a spindle rotatable on adjustment of the cover member to the heating apparatus.

Advantageously the casing of the fan or blower constitutes a part of the entire casing, that is, the casing inclosing the valves and means for varying the temperature of the air passing through the apparatus also incloses the fan or blower, and thus the whole of the apparatus is inclosed in a casing of regular form and constitutes a serviceable single unit casing wherein all the parts are so arranged that practically the whole of the interior of the casing is employed.

The means for varying the temperature of the air, comprises a nest or plurality of tubes of comparatively short length and small bore, the plurality providing a large contacting surface for the air and the small bore causing the air currents to be divided into comparatively very thin streams which are quickly affected by the temperature of the cooling or heating medium and thereby enable tubes of short length to be employed with advantage.

In a single unit apparatus comprising the above features the temperature controlling means in the form of a large number of tubes of short length and small bore is arranged in the lower part of the casing with the tubes vertically or horizontally disposed in a casing connected with means for supplying a heating or cooling medium thereto. The lower part of the casing is in communication with preferably a single orifice leading to distributing conduits, and is also fitted with a valve whereby air currents from the fan may be directed through the

nest of tubes before passing to the said orifice, or alternatively directed to the orifice without passing through the tubes. Such valve is so disposed in the casing relatively to the said nest of tubes that when the air is passed direct to the orifice the nest of tubes is practically cut off from the other part of the casing thereby obviating the presence of circulating or eddy currents around the temperature means. This valve may comprise a single hinged or pivoted member and serves as a means for placing the temperature means in and out of use, as well as controls the quantity of air passing through the temperature means and clear of such means.

The invention will be further described in connection with the accompanying drawings, wherein:

20 Figure 1 is a sectional elevation of a single unit heating, cooling and ventilating apparatus constructed according to this invention;

25 Fig. 2 is a vertical section taken on the line 2—2 of Fig. 1;

Figs. 3 and 4 are sectional plans taken on the lines 3—3 and 4—4 respectively of Fig. 1;

Fig. 5 is a detail hereinafter described.

30 Referring to the drawings *a* designates the fan or blower and *b* the air trunk casing which incloses the fan and communicates with a compartment *c*. A similar compartment *d* is separated therefrom by a division member *e*. The compartment *d* is shown as being in communication at one end with the opening *f* leading to the air, and at the other end with the eye *g* of the fan; while the compartment *c* is connected at one end with 35 the air trunk *h* and at the other end with the chamber *j* containing a directing valve *k*. The chamber *j* connects at one part with a compartment *l* leading to one end of the temperature changing means *m*, and at another part with a chamber *n* leading direct to an orifice *o* communicating with distributing conduits *p*.

The temperature changing means *m* comprises a comparatively great number of tubes 50 *m*¹ of small bore and short length disposed within a casing *m*². This nest of tubes is mounted between plates *m*³ which serve to inclose the same and prevent the circulation of air therearound. The casing *m*² is fitted 55 with valve controlled connections *m*⁴ for the supply of heating or cooling medium to the casing *m*².

The arrangement and construction of the temperature changing means is extremely 60 compact and efficient and serves to divide the air currents into a great number of thin streams which are very quickly affected by their frictional contact with the inner surfaces of the tubes of small bore.

65 The fan *a* is disposed above the tempera-

ture changing means *m* within the general casing of the unit, being separated from the temperature changing means by a diaphragm *q* and the fan casing *b* which subdivide the general casing into upper and 70 lower compartments; the fan casing is contained within the upper compartment to one side thereof, the side wall *a*¹ of the fan casing constituting a continuation or part of the division member *e* which separates the 75 compartments *c*, *d*, containing the valves *r* and *s*. These valves *r* and *s* are interdependent in their operation and serve to control the direction of flow of the air currents through the apparatus, being operated 80 through the medium of mechanism shown in Fig. 1 and in detail in Fig. 5. Such mechanism comprises two spindles *r*¹ and *s*¹ in alinement, one being actuated from the other in a reverse direction through the medium 85 of quadrant racks *t*, a spindle *u*, levers *v* and link *w*, a handle *x* being provided on the end of one of the spindles for actuating the mechanism.

The valves *r* and *s* are of curved construction as is apparent from Fig. 1, and are so connected to their corresponding spindles, and adapted to operate as to be balanced.

The position of these valves shown in Fig. 1 is that for the entry of air through 95 the inlet *f* past the valve *s* to the eye *g* of the fan, thence to the fan trunk *h* past the valve *r* to the chamber *j* and to the conduits *p* by way of the means *m* or chamber *n* or both. When the valves *r* and *s* are reversed 100 the inlet is connected with the trunk *h* and the chamber *j* with the fan eye *g* by way of valve *s*.

The air passing from the compartment *c* to the compartment *j* passes on either to the 105 chamber *l*, or to the chamber *n* or partly to each according to the position of the valve *k*, the position shown directing air through each chamber. When the valve *k* is moved to a vertical position closing the chamber *l*, 110 the temperature changing means is entirely cut off from the air currents and circulation thereof around such means is entirely prevented.

The fan is driven by a suitable motor *y* 115 mounted on the general casing of the apparatus.

I claim:

1. A heating, cooling, and ventilating apparatus, comprising an outer casing subdivided in its upper part to form two chambers, a fan arranged in one chamber with the eye of the fan communicating with the other chamber, a temperature varying means below said chambers, a communication with 120 atmosphere and a communication with the said temperature varying means for each said chamber, a control valve in each chamber adapted to close either of said communications in its respective chamber, said valves 125 130

being connected for simultaneous movement and disposed so that one closes its respective communication to atmosphere while the other closes its respective communication 5 with said temperature varying means.

2. A heating, cooling and ventilating apparatus comprising an outer casing sub-divided in its upper part to form two chambers, a fan arranged in one chamber with 10 the eye of the fan communicating with the other chamber, a diaphragm sub-dividing the lower part of said outer casing, a temperature varying means fixed beneath said diaphragm, a distributing duct below said 15 temperature varying means, a communication from each of said chambers in the upper part of the outer casing, through said diaphragm and said temperature varying means to said distributing duct, and 20 through said diaphragm direct to said distributing duct, a single regulating valve disposed to simultaneously control all of said communications, a communication for each of said chambers with the atmosphere, 25 a control valve within each said chamber adapted to close either of its respective communications with atmosphere, or the communication with said temperature varying means, said control valves being connected 30 for simultaneous movement and disposed so that one closes its respective communication to atmosphere while the other closes its respective communication to said temperature varying means.

3. A heating, cooling and ventilating apparatus comprising an outer casing sub-divided in its upper part to form two chambers, a fan arranged in one chamber with 35 the eye of the fan communicating with the other chamber, a diaphragm subdividing the lower part of said outer casing, a temperature varying means fixed beneath said diaphragm, a distributing duct below said temperature varying means, a communication 40 from each of said chambers in the upper part of the outer casing, through said diaphragm and said temperature varying means to said distributing duct, and through said diaphragm direct to said 45 distributing duct, a single regulating valve disposed to simultaneously control all of said communications, a communication for each of said chambers with the atmosphere, an

arcuate control valve within each said chamber adapted to close either of its respective 55 communications with atmosphere, or the communication with said temperature varying means, a spindle for each valve arranged in alignment one with the other, and the valves fixed thereto respectively so that 60 one closes its respective communication to atmosphere while the other closes its respective communication to said temperature varying means, and means for actuating said valves consisting of a lever on one valve 65 spindle and outside said outer casing a toothed quadrant on said spindle, a second toothed quadrant gearing with the said first mentioned quadrant and mounted on a rotatable axis, a lever fixed to said axis, a lever 70 fixed to the other valve spindle, and a link connecting said last mentioned levers.

4. A heating, cooling and ventilating apparatus comprising an outer casing sub-divided in its upper part to form two chambers, a fan casing occupying an end in one chamber, with the eye of the fan opening into the other chamber, a temperature varying means below said chambers, a communication with atmosphere and a communication 75 with said temperature varying means for chamber and contained fan casing, and the other chamber with which the eye of the fan communicates, an arcuate control valve in each said chamber adapted to close either 80 of said communications in its respective chamber, a spindle for each valve, quadrant and link mechanism connecting said spindle as set forth, the valves being mounted on their respective spindles for simultaneous 85 movement and disposed so that one closes its respective communications to atmosphere while the other closes its respective communication with said temperature varying 90 means, a regulating valve arranged in the communication between said fan casing and said temperature varying means, a distribution duct below said temperature varying means, means connecting said temperature varying means and said distribution duct, 95 and a communication from said regulating valve direct to said distribution duct substantially as set forth.

In testimony whereof I affix my signature.

THOMAS NEILSON.
